UNITED STATES PATENT OFFICE

2,477,362

TOILET TISSUE DISPENSER

Silvestro Cavalieri, Chicago, Ill.

Application April 8, 1946, Serial No. 660,565

3 Claims. (Cl. 242—55.2)

1

This invention relates to a new and useful improvement in toilet tissue dispensers and particularly to a dispenser which is designed to support toilet tissue of the type which is formed of a continuous strip wound about a cardboard or other tube into a roll. Dispensers of this type are generally of one or the other of two kinds. One kind supports the roll by a supporting member which will permit the strip of tissue to be unwound continuously; that is, it will permit the roll to turn around and around indefinitely without stopping. The other type of dispenser is so arranged as to permit the tissue roll to make but a single revolution, means being provided to stop the unwinding operation after the roll has made approximately one revolution.

The present dispenser is designed to have the combined advantages of the two types of dispensers above referred to. Stop means are provided so that, normally, the toilet paper roll will make but a single revolution as a result of one unwinding operation, but several turns of the paper may be removed without necessitating more than one forward and backward rotary movement of the roll.

It is believed that the invention will be readily understood from a detailed description thereof taken in connection with the accompanying drawings in which

Fig. 1 is a side view of the dispenser mounted upon a supporting wall, as in a bathroom, showing a roll of toilet paper supported thereon, and

Fig. 2 is a perspective view of the device.

Referring now to the drawings, in which like reference characters indicate the same parts in both views, 1 is a wall plate adapted to be secured to the wall of a toilet or any other desired surface by screws, nails or similar devices. A pivot rod or support 2 has its inner end 3 firmly fixed to plate 1 by any means desired and extends outwardly therefrom, a distance somewhat greater than the length of a toilet paper roll.

It may be here explained that the fixture may be formed of metal, plastic or even wood. The manner in which the end 3 of rod 2 will be secured to plate 1 will depend on the material of which they are made. A framework or reel 4 is rotatably supported on the rod 2 as will be presently explained. Two oblong end pieces or brackets 5 and 6 are provided as shown in the drawings. Extending between the end pieces 5 and 6 is a pair of roll supporting bars 7 and 8, each of which has its opposite ends fixed to like ends of the elongated end pieces 5 and 6, respectively. Thus, bar 7 has one end joined to end piece 5 and

2

its other end to end piece 6. Bar 8 is arranged in a similar manner. Bars 7 and 8 may be secured to end pieces 5 and 6 by screws, glue, clamps or, if the device is formed of plastic, the parts may be molded into an integral whole.

End pieces 5 and 6 are provided with the openings 9 and 10, respectively, which are similarly positioned eccentrically of the end pieces. The rod 2 is arranged to be received by the holes 9 and 10 to pivotally support the reel 4. A cotter pin 11 is provided to retain the reel 4 on the rod 2. As shown in the drawings, the end pieces are arranged at substantially right angles to the rod 2, and the bars 7 and 8 are arranged generally parallel thereto, but preferably diverging slightly from each other. Thus, the end piece 5 may be slightly larger than end piece 6 so that the reel 4 will be somewhat tapered. The reel 4 will be as long as or slightly longer than the toilet paper roll with which it will be used and of a size which will permit the tubular center of a toilet tissue roll to be snugly slipped thereon.

Fixed to mounting plate 1 is a stop 12 which is positioned in the path of stop 13 on end member 5 so as to limit the movement of the roll to one nearly complete revolution.

As the holes 9 and 10, in end pieces 5 and 6, are positioned nearer the bar 7 than bar 8, when at rest, the reel 4 and the roll carried thereby 30 will tend to assume a position with the supporting bar 8 substantially lowermost.

In using the present fixture, the central tube or spool of the tissue roll will be fixed onto the reel 4 so it will remain firmly thereon. The parts 35 should be so proportioned that the inner end of the roll will be adjacent to the end piece 5 when properly positioned on the reel 4. Now, if the end 14 of the paper be pulled downwardly, the roll will rotate until stop 13 engages stop 12 and prevents further movement. The end 14 of the tissue, up to the top of the roll, may be readily torn off whereupon the roll will return to its 40 normal position of rest with bar 8 lowermost.

If it is desired to remove several turns of the 45 tissue strip from the roll at one time, the end 14 of the strip will be grasped and, by a sort of circular movement of the hand about the roll, as many turns may be unwound as is desired. This is made possible by the fact that the rod 2 is supported at one end only, the outer end of the fixture being free and open to permit the ready 50 unwinding of the paper strip therefrom.

While applicant's preferred embodiment of the invention has been disclosed herein, many modifications in material, form and proportions may

be made in the invention without departing from the spirit thereof. As for instance, the rod 2 may be mounted directly on the supporting surface as by a driven or screw-threaded fastening or the like. The scope of the invention should thus be limited only by the scope of the claims.

Having thus described my invention, what I claim as new and desire to secure by Letters Patent of the United States is:

1. In a toilet tissue dispenser, a wall plate, a pivot rod, means for fixing the inner end only of said rod to the said plate, and at right angular relation thereto, a roll supporting member comprising a pair of oblong end pieces rotatably mounted on said rod in spaced relation, the said end pieces being similarly arranged eccentrically about said pivot rod, and a pair of roll supporting bars, each of said bars having its opposite ends fixed with like ends of said end pieces, respectively, a stop fixed with one of said end pieces, and a fixed stop mounted in the path of the stop on the said end piece to limit the rotation of said roll supporting member.

2. In a toilet tissue dispenser, a wall plate, a pivot rod, means at one end only of said rod for fixing said rod to said wall plate and at right angular relation thereto, a roll supporting member comprising a pair of elongated end pieces rotatably mounted on said rod in spaced relation, the said end pieces being similarly arranged eccentrically about said pivot rod, and a pair of generally parallel roll supporting bars arranged to receive a roll of toilet paper thereon, each of said bars having its opposite ends fixed with like ends of said end pieces, respectively, a stop fixed with

one of said end pieces, and a fixed stop mounted on said wall plate in the path of the stop on the said end piece to limit the rotation of said supporting members.

3. In a toilet tissue dispenser, a wall plate, a pivot rod, means at one end only of said rod for fixing said rod to said plate and at substantially right angular relation thereto, a roll supporting member comprising a pair of end pieces rotatably mounted on said rod in spaced relation, the said end pieces being similarly arranged eccentrically of said rod, and a pair of toilet tissue roll supporting bars arranged generally parallel to said rod, each of said roll supporting bars having its opposite ends fixed with like ends of said end pieces, respectively, a stop fixed with one of said end pieces, and a fixed stop mounted in the path of the stop on the said end piece to limit the rotation of said supporting member, the end of said roll supporting member remote from said wall plate being free and unobstructed.

SILVESTRO CAVALIERI.
